UNITED STATES PATENT OFFICE.

WILLIAM JOHN PALMER, OF NORTHWILKESBORO, NORTH CAROLINA.

BEARING.

1,348,042.

Specification of Letters Patent.

Patented July 27, 1920.

Application filed November 24, 1919. Serial No. 340,387.

To all whom it may concern:

Be it known that I, WILLIAM J. PALMER, a citizen of the United States, residing at Northwilkesboro, in the county of Wilkes 5 and State of North Carolina, have invented new and useful Improvements in Bearings, of which the following is a specification.

This invention has reference to grinding mills, and more particularly to mills used 10 for grinding corn and other grain in which the grain is subject to a grinding action between two stones one of which being revolvable and the other stationary.

In this class of mills the bearings for the 15 revolvable mill stone not infrequently permit of such movement of the said stone as to allow the burs on the face thereof to be brought into excessive frictional engagement with the bur face of the co-acting mill stone, and as a result the usefulness 20 of the stones is materially impaired.

It may therefore be considered the object of the present invention to provide means, in the nature of a bearing which 25 permits of the proper adjustment with respect to the space between the bur or grinding faces of the mill stones and which will positively prevent such faces being brought into frictional contacting engagement.

30 A further object of the invention is to produce a bearing for the operating shaft of a grist mill which will prevent or limit the movement of the mill stones with respect to each other and which shall be of an extremely simple construction so that the 35 same may be attached to any ordinary grist mill.

The foregoing objects, and others which 40 will appear as the nature of the invention is better understood may be accomplished by a construction, combination and operative arrangement of parts such as is illustrated by the drawings.

In the drawings:

45 Fig. 1 is a side elevation of a grist mill provided with the improvement.

Fig. 2 is a plan view thereof.

Fig. 3 is a sectional view approximately on the line 3—3 of Fig. 2.

50 Fig. 4 is a perspective view of the frame for the shaft illustrating the application of the improvement.

Fig. 5 is a detail enlarged perspective view of the improvement attached to the 55 shaft, parts being broken away and parts being in section.

Referring now to the drawings in detail, the numeral 1 designates a grist mill of the ordinary construction, the same comprising two hollow sections 2 and 3. In the section 2 is the non-rotatable mill stone 4, while in the section 3 is the rotatable mill stone 5. The shaft for the rotatable mill stone 5 is indicated by the numeral 6, and the same is provided with the usual screw 60 7 that passes through the elongated central opening in the mill stone 4 and provides a conveyer for the grain from the hopper to between the mill stones. The mill stones 4 and 5 have their confronting faces burred 65 70 in the usual manner.

The shaft 6, in the present instance is mounted in bearings 8 and 9 provided upon the opposite ends of a substantially rectangular frame 10 that is suitably supported 75 to one side of the mill casing and on the shaft 9, approximately centrally of the frame 10 is the pulley wheel 11. The frame 10 has its outer side provided with an extending portion 12 having a lateral portion 80 on the outer end thereof which is in the nature of a head 13, and this head is provided with a threaded opening receiving therein a screw 14 operated by a hand wheel 15. This screw has its inner end loosely 85 connected with or binding against a cup-shaped member 16 that provides one of the elements of a race-way for anti-frictional balls 17. The other element of the race-way, indicated by the numeral 18 finds 90 a bearing in the end of the shaft 6.

On its opposite side the frame 10 is provided with an enlargement 19 through which the shaft 6 passes. On the shaft 6, and contacting with the inner face of the 95 enlargement is a cup-shaped member 20, and in this cup-shaped member are anti-frictional balls 21. These balls are contacted by a disk member 22 that is forced in engagement therewith by a spring 23 that surrounds the shaft 6. On the shaft 6 is a collar 24. This shaft is held adjustable on the shaft through the medium of a binding element in the nature of a bolt 25. The spring 23 exerts a pressure between the member 22 100 and the collar 24 so that the shaft is normally retained in one position and so that the fixed mill stone 5 can not move toward the mill stone 4 unless the screw 14 is manipulated. By manipulating the screw 14 it 105 will be apparent that the confronting or bur faces of the mill stone may be properly ad-

justed, and by adjusting the collar 24 on the shaft 6 it will be likewise apparent that the tension of the spring 23 may be adjusted.

It is thought, from the foregoing description, when taken in connection with the drawings, the simplicity of the construction and the advantages thereof will be apparent without further detailed description.

Having thus described the invention, what is claimed as new, is:—

In combination with a grist mill having a stationary grinding stone, a revoluble grinding stone, a shaft for the latter, means for moving the shaft longitudinally, a frame 15 on which the shaft is journaled, and means for revolving the shaft; of a bearing for holding the shaft against accidental longi-

tudinal movement to prevent the confronting faces of the mill stones being brought into excessive frictional engagement, said bearing comprising a cup member loosely mounted on the shaft and having its closed face contacting with one of the sides of the frame, anti-frictional elements in said cup-shaped member, a disk member loose on the shaft received in the cup-shaped member and contacting with the anti-frictional elements therefor, a spring surrounding the shaft and contacting with the disk, and an adjustable collar on the shaft and engaging with the spring.

In testimony whereof I affix my signature.

WILLIAM JOHN PALMER.
